[57] CLAIM

The ornamental design for a water bottle liner, as shown and described.

DESCRIPTION

FIG. 1 is front elevational view of the water bottle liner in full lines with a water bottle in broken lines representing environmental association matter being for illustrative purposes only and forming no part of the claimed invention, the rear elevational view being a mirror image of the front view. FIG. 2 is a right side elevational view thereof, the left side elevational view being a mirror image of the right side view. FIG. 3 is a top plan view of the water bottle liner; and, FIG. 4 is a bottom plan view thereof.
